UNITED STATES PATENT OFFICE

149,536

DESIGN FOR A MOTION-PICTURE CAMERA

Walter H. Bach, Los Angeles, Calif., assignor to
Berndt-Bach, Incorporated, a corporation of
California

Application October 31, 1947, Serial No. 142,246

Term of patent 14 years

(Cl. D61—1)

To all whom it may concern:

Be it known that I, Walter H. Bach, citizen of the United States of America, residing in the city of Los Angeles, in the county of Los Angeles, State of California, have invented a new, original, and ornamental Design for a Motion-Picture Camera, of which the following is a specification, reference being had to the accompanying drawing, forming a part thereof.

Figure 1 is a perspective view of a motion picture camera showing my new design;

Fig. 2 is a rear elevational view of the article shown in Fig. 1;

Fig. 3 is a side elevational view of the opposite side of the disclosure in Figure 1; and

Fig. 4 is a top plan view thereof.

I claim:

The ornamental design for a motion-picture camera, substantially as shown.

WALTER H. BACH.
